FLOOR DRAIN

Wells S. Fleming, Chicago, Ill., assignor to Fleming Manufacturing Company, Chicago, Ill., a corporation of Illinois

Application July 27, 1934, Serial No. 737,273

5 Claims. (Cl. 182—31)

Floor drains generally consist of a tubular part, or section, having a cup-like, lateral flange on which seats a clamping plate, for clamping a sheet of waterproofing material down on said flange. Water will collect more or less in said flange and must be drained off. And, in case of heavy rains, water is likely also to back up around the exterior of the tubular section of the drain body, and moisten the cementitious material 10 forming the top surface of the floor. This condition, in case of freezing weather, would tend to break up the floor surface, and therefore should be prevented.

My floor drain incidentally is adapted to drain off the water collecting exterior of the drain 15 section into the pendent tubular portion of the drain body; and further to prevent water, under back pressure, as in a heavy rain, from being driven into contact with the top finish of the 20 floor.

A further object of my invention is to provide simple means, in the sheet clamping parts of the floor drain, which will serve to cut out a 25 circular portion of the waterproofing sheet; the circular opening so produced being arranged to receive the drain section of the floor drain.

I accomplish this cutting out operation by providing the opposed faces of the parts, between which the waterproofing sheet is clamped, with 30 cooperating means, whereby, when the clamping plate is forced down on the flange of the body section, a circular portion of the said sheet is removed so that the sheet will fit neatly on the flange of the drain body. By such means I reduce to a simple job what frequently is a difficult task; and besides the floor drain will have a 35 better fit with the waterproofing sheet. Furthermore, the making of the bolt holes thru the waterproof sheet is eliminated, which, if carelessly done, is apt to cause leaks thru the waterproofing sheet.

A further object of my invention is to provide a relatively simple, as well as efficient, device, by 40 which the above mentioned objects may be attained.

The details of my floor drain fixture are hereinafter fully described with reference to the accompanying drawing.

50 In the drawing: Fig. 1 shows a portion of a floor section with my floor drain installed. This figure shows the cutting out elements of the clamping parts of my floor drain as having been operated to cut out a circular portion of the waterproofing sheet,

and said sheet as firmly clamped in my floor drain;

Fig. 2 shows a section on the line 2—2 of Fig. 1;

Fig. 3 shows a fragmentary section of one embodiment of means in the sheet clamping parts 5 of my floor drain which serve to cut out a circular portion of the waterproofing sheet;

Fig. 4 shows another embodiment of said feature; and

Fig. 5 shows the installation of the type of my 10 floor drain shown by Fig. 4.

a and *a'* of Fig. 1 show the lower and upper sections of the concrete floor separated by waterproofing sheet *b*, which is clamped in my floor drain.

15

My floor drain consists of a body section *c*, having a pendent tubular portion *c'* adapted to be connected to a drain pipe; and it is formed with a lateral cup-like flange *c2*. Said cup-like flange is provided with an interior recess *d*, en- 20 compassed by an annular shoulder *d'* having a vertical face. *e* is a clamping plate adapted to seat in the flange *c2* as shown, for example, in Fig. 1. It is provided with a vertical annular rib *f* of knife-edge cross-section, the outer face 25 of which rib seats on the edge of the shoulder *d'*; and when said clamping plate is placed on top of the flange and tapped lightly, for example with a hammer, the rib *f* will function to cut out a circular portion from the waterproofing 30 sheet *b*. Such cutout piece is then removed, thus leaving a circular opening for the insertion of the tubular drain section *h*. The opening in the sheet thus provided avoids the cutting of bolt holes thru the waterproofing sheet *b*, which hole 35 cutting operation, if improperly performed, is apt to set up leaking conditions.

With the arrangement of my device, and the mode of clamping the waterproofing sheet between its clamping member, a waterproofing 40 sheet once having had a circular portion cut out for the drain section and clamped in place requires no further cutting operations.

Instead of making the cup-like flange *c2* of the body section with a recess, and the clamping plate 45 with the cutter as mentioned, as shown by Figs. 1 and 2, said sheet cutting elements may be reversed as shown by Figs. 4 and 5, in which *c3* represents the body section of my floor drain, the cup-like flange of which is provided with an 50 upstanding projecting annular cutting rib *f'* which cooperates with the annular shoulder *d2* of the clamping plate *e'*.

The embodiment of my invention shown in Fig. 4 operates in other respects—as illustrated by 55

Fig. 5—in the same way as the embodiment of my invention shown by Figs. 1 and 3. The unessential details of my invention may, of course, be varied to suit the manufacturer.

5. The essential features of my invention are particularly described by the following claims.

Thus I claim:

1. In a floor drain, a body having a pendent tubular portion provided with a circumferential lateral cup-like flange and adapted to be connected to a drain pipe, and an annular clamping plate fitting in and bolted on said flange, said flange and said clamping plate being adapted to clamp a water-proofing sheet between their outer peripheral portions, the opposed faces of said flange and said clamping plate being provided with cooperating means, whereby to cut out a circular portion from said water-proofing sheet.
2. In a floor drain, a body having a pendent tubular portion provided with a circumferential lateral cup-like flange and adapted to be connected to a drain pipe, and an annular clamping plate fitting in and bolted on the inner peripheral portion of said flange, said flange and said clamping plate being adapted to clamp a water-proofing sheet between their outer peripheral portions, the opposed faces of said flange and said clamping plate being provided with cooperating means, whereby to cut out a circular portion from said water-proofing sheet and to do away with the necessity of making bolt holes in said sheet in order to bolt said clamping plate to said flange.
3. In a floor drain, a body having a pendent tubular portion provided with a circumferential lateral cup-like flange and adapted to be connected to a drain pipe, and an annular clamping plate fitting in and bolted on said flange, said flange and said clamping plate being adapted to clamp a water-proofing sheet between their outer peripheral portions, one of the opposed faces of said flange and said clamping plate being provided with an interior recess encompassed by an annular shoulder having a vertical face, the other provided with a vertical annular rib of knife-edge cross section, the outer face of said rib seating on

the edge of said shoulder, whereby to cut out a circular portion from said water-proofing sheet.

4. In a floor drain, a body having a pendent tubular portion provided with a circumferential lateral cup-like flange and adapted to be connected to a drain pipe, an annular clamping plate fitting in and bolted on said flange, said flange and said clamping plate being adapted to clamp a water-proofing sheet between their outer peripheral portions, and a tubular drain section having its lower end threaded into said body and extending a substantial distance below the flange of the latter, thereby providing an obstruction to water under back pressure passing to the exterior of said drain section, the opposed faces of said flange and said clamping plate provided with cooperating means, whereby to cut out a circular portion from said water-proofing sheet for receiving said drain section.

5. In a floor drain, a body having a pendent tubular portion provided with a circumferential lateral cup-like flange and adapted to be connected to a drain pipe, an annular clamping plate fitting in and bolted on the inner peripheral portion of said flange, said flange and said clamping plate being adapted to clamp a water-proofing sheet between their outer peripheral portions, and a tubular drain section having its lower end threaded into said body and extending a substantial distance below the flange of the latter, thereby providing an obstruction to water under back pressure passing to the exterior of said drain section, one of the opposed faces of said flange and said clamping plate being provided with an interior recess encompassed by an annular shoulder having a vertical face, the other being provided with a vertical annular rib of knife-edge cross-section, the outer face of said rib seating on the edge of said shoulder, whereby to cut out a circular portion from said water-proofing sheet for receiving said drain section and to do away with the necessity of making bolt holes in said sheet in order to bolt said clamping plate and said flange together.
